(57) **CLAIM**

The ornamental design for a physiotherapy apparatus, as shown and described.

DESCRIPTION

FIG. 1 is an upper perspective view of a physiotherapy apparatus showing our new design.

FIG. 2 is a front view thereof;

FIG. 3 is a rear view thereof.

FIG. 4 is a side view thereof, an opposite side view being a mirror image thereof; and,

FIG. 5 is a top plan view thereof.

The physiotherapy apparatus is an active balance support designed to assist patients suffering with mild leg weakness, for example as a result of neurological problems such as a stroke, an accident, age or illness.
